United States Patent Office

Des. 232,576
Patented Aug. 27, 1974

232,576

SPINNING TOY

Michael Langieri, Butler, N.J., assignor to
Questor Corporation, Toledo, Ohio

Filed Oct. 2, 1972, Ser. No. 297,691

Term of patent 14 years

Int. Cl. D21—01

U.S. Cl. D34—15 CC

Fig. 1.

Fig. 2.

Fig. 3.

FIG. 1 is a perspective view of a spinning toy showing my new design;

FIG. 2 is a top plan view thereof; and

FIG. 3 is a side elevational view thereof.

I claim:

The ornamental design for a spinning toy, as shown.
